GAUGE

Warren Ames, Newton, Mass.

Application November 22, 1933, Serial No. 699,148

19 Claims. (Cl. 33—172)

My invention relates to gauges, and particularly but not exclusively to so-called dial micrometer gauges.

The invention, which has among its objects the provision of a gauge which will stand rough usage, will be best understood from the following description when read in the light of the accompanying drawing, while the scope of the invention will be more particularly pointed out in the appended claims.

In the drawing:—

Figure 1 is a rear elevation of a gauge, constructed according to the invention, with the back plate removed;

Fig. 2 is a section on the line 2—2 of Fig. 1 with parts shown in elevation and with the back plate in position;

Fig. 3 is a plan of the rear side of the front plate with part of the mechanism carried by said plate removed;

Fig. 4 is a section on the line 4—4 of Fig. 1 with parts omitted, the section line 4—4 also appearing on Figs. 3 and 8 for convenience in co-ordinating the showing of these figures;

Figs. 5 and 6 are sections on the lines 5—5 and 6—6 of Fig. 1;

Fig. 7 is a perspective view of the contact feeler actuated member;

Fig. 8 is a bottom view of the rack supporting or frame member carried by the front plate, a top view or plan of which member is shown by Fig. 1; and

Fig. 9 is a plan of the leaf spring acting upon the dial plate.

Referring to the drawing, the present embodiment of the invention includes a casing or support having a ring-shaped casing member 1, and a back plate 3 removably secured to the casing member 1 by a plurality of screws 5, the screw holes for which latter are indicated at 7 in Fig. 1.

At the front side of the casing is a front plate 9 removably secured to the casing member 1 by a plurality of screws 11 which, as is apparent from the drawing, are readily accessible when the back plate is removed.

Herein the gauge is provided with a bezel ring 13 which carries the crystal 15. As shown, the bezel ring is formed interiorly with a reduced diameter portion 17 which fits over the casing member 1, the shoulder 19 on the bezel ring, formed as a result of this reduced diameter portion, resting on the outer surface of the front plate 9.

For rotatably and removably securing the bezel ring to the front plate, the former is formed with

an interior annular groove 21 adapted to receive the end portions of a plurality of retaining members 23 carried by the front plate. As shown, the inner face of the front plate is formed with radially extending grooves 25 in which the retaining members 23 slidably fit. Each retaining member is adapted to be clamped to the front plate by a set screw 27 tapped into the retaining member, the set screw extending through a radially extending slot 29 in the front plate and having its head 30 at the inner side of the latter. When the retaining members are clamped in their positions shown by Figs. 1 and 5 of the drawing, the bezel will be rotatably secured to the front plate. By loosening the screws 27 the retaining members may be slid radially toward the center of the front plate into their positions shown by Fig. 3, so as to withdraw the retaining members from the annular groove 21, which will permit the bezel ring to be removed from the front plate.

As shown, the dial plate 31 of the gauge is received in the reduced diameter portion 33 of the bezel ring with its edges abutting against the shoulder 35. The triangular shaped leaf spring 37, inserted between the dial plate and the front plate, holds the dial plate frictionally in engagement with the shoulder 35, so that when the bezel ring is rotated relative to the front plate and casing member 1 the dial plate will rotate with it. In this way the indicator hand or member 39 may be adjusted relative to the dial plate for initially setting the indicator hand on the zero mark of the dial, as will be understood by those skilled in the art.

In the present form of gauge, the indicator hand 39 is mounted on a rotatable post 41 (Figs. 2 and 4) to which is fixed a center pinion 43 meshing with a gear 45 fixed to a spindle 47. The spindle 47 at opposite ends is rotatably supported in bearings 49 and 51 formed in the front plate 9 and in a frame member 53 respectively. As shown, this frame member is carried by the front plate, and is secured thereto by screws 55.

The frame member 53, as shown, is formed on its upper side with a rectangular slot 57 in which is reciprocally mounted a rack bar 59 having rack teeth 61. As shown, the rack is retained in the slot by a plate 63 having a pair of laterally projecting portions 65 which rest against the upper side of the rack and hold it within the slot. As illustrated, the plate 63 is secured to the frame member 53 by screws 64, and is formed at one end with a projecting portion 67 to which is secured one end of a spring 69, the other end of which

latter is attached at 71 to the rack so as to urge the rack downwardly with the gauge in the position shown by Fig. 1.

Meshing with the teeth 61 of the rack is a rack pinion 73 fixedly secured to an internal sleeve 75 rotatably mounted on the spindle 41. Fixedly secured to the lower end of the sleeve 75 is a radially projecting arm 77 which cooperates with a vertically extending pin 79 carried by the gear 45.

In the present embodiment of the invention the front plate has rotatably mounted thereon a gear 81 which meshes with the center pinion 43, the gear being urged to rotate by a hair spring 83 in such direction as will rotate the gear 45, through the center pinion 43, to cause the arm 77 normally to contact with the pin 79 carried by the gear 45. As shown, the hair spring is attached at its inner end (Fig. 3) to the hub 84 of the gear 81, and at its outer end (Fig. 8) to the frame member 53 at 85.

As shown, the casing member 1 is provided with a lateral screw threaded perforation 86, into which is removably screw threaded an elongated guide member 87. Reciprocally mounted in the perforation of the guide member is a contact feeler rod 89, which latter at its lower end carries a member 91, the lower end surface of which contacts the work, this member having the shank 93 removably screw threaded into the end of the rod. At its inner end, the rod 89 is shown as formed with a head 95 provided with an extending portion 97. As clearly illustrated in Fig. 2, the outer end of the head 95, in the assembled gauge, abuts with the end of the rack 59, with the flattened face 99 of the projecting portion 97 of the head resting against that side of the rack which is adjacent the back plate. This construction prevents rotation of the rod 89 in the bearing sleeve 87.

It will be observed the hereinbefore described construction provides that the entire internal gauge mechanism, and the dial and bezel, are mounted solely on the front plate 9, and that, after the front plate with these parts assembled thereon is secured to the casing member 1, the bearing sleeve 87, carrying the rod 89 and associated contact feeler 91, may be screwed into the perforation 86 to place the rod into operative relation with the rack. This construction provides against strains on the rod 89 being communicated to the rack, and eliminates the defects of gauges as heretofore constructed in which the rod and rack are made as an integral part mounted for reciprocation in the casing member 1, with the rack pinion mounted for rotation on the front plate.

Further, it has been found that dust and dirt, which collect on the rod 89 when the gauge is in use, have a tendency to work into and cause wear of the bearing in which it is reciprocally mounted, resulting in a minute lateral loose play of the rod, which causes a canting of the same when the member 91 carried thereby is pressed against the work. With gauges as heretofore constructed, in which the rod 89 has been made integral with the rack, this canting causes improper meshing of the rack with the rack pinion, resulting in binding and wear of the gear teeth, and inaccurate measurements. This defect is entirely eliminated by the present invention.

It will also be observed that the hair spring 83 so urges the gear 45 which carries the stop member formed by the pin 79 as to move said pin in the same direction as that in which the cooperating stop member formed by the arm 77 is moved

by the rack pinion when the rack 59 is pushed inwardly by the contact feeler rod 89. In other words, when the contact feeler rod is pushed inwardly, the arm 77 tends to move away from the pin 79, and the spring 83 tends to cause the pin to follow the arm. This construction provides, that if the gauge is dropped or clumsily or otherwise handled, to cause the contact feeler rod 89 to be violently driven inwardly, the blow imparted to the rack will not be imparted to the train of gearing beyond the rack pinion. It will be understood that the gauge herein illustrated is commonly made much smaller than shown in the drawing, with the result that the gear teeth are very delicate, yet the train of gearing and parts operated thereby have considerable inertia. With gauges as heretofore constructed this violent inward movement of the contact feeler rod when subjected to blows commonly strips or otherwise damages the gears. This defect of gauges as heretofore constructed is eliminated by the present invention.

It will be understood that wide deviations may be made from the embodiment of the invention herein illustrated without departing from the spirit of the invention.

I claim:

1. A dial micrometer gauge having, in combination, a casing having an opening and a removable member closing said opening, a movable indicator member and motion transmitting means for moving it operatively carried solely by said removable member, said motion transmitting means being wholly within said casing and being of such dimensions relative to the dimensions of said opening that when said member of said casing is removed said means is removable through said opening while attached to said member, and a contact feeler actuated part cooperating with said motion transmitting means for operating it, said part being carried by said casing independently of said removable member and being operatively separable from said motion transmitting means.

2. A dial micrometer gauge having, in combination, a casing having an opening and a removable member closing said opening, a movable indicator member and motion transmitting means for moving it operatively carried solely by said removable member, said motion transmitting means being wholly within said casing and being of such dimensions relative to the dimensions of said opening that when said member of said casing is removed said means is removable through said opening while attached to said member, a contact feeler actuated part operatively contacting with said motion transmitting means for operating it, and spring means for urging said part and means into contact, said part being carried by said casing independently of said removable member and being operatively separable from said motion transmitting means.

3. A dial micrometer gauge having, in combination, a casing having an opening and a removable front plate closing said opening, a movable indicator member operatively carried by said front plate, multiplying motion transmitting means comprising a reciprocatory member, which means including said reciprocatory member thereof is wholly within said casing and is mounted solely on said front plate, said means being of such dimensions relative to said opening that when said front plate is removed said means is removable through said opening while attached to said front plate, and a contact feeler actuated part movably mounted on said casing independ-

ently of said front plate for actuating said reciprocator member.

4. A dial micrometer gauge having, in combination, a casing having an opening and a removable front plate closing said opening, a movable indicator member operatively carried by said front plate, multiplying motion transmitting means comprising a reciprocator member, which means including said reciprocator member thereof is wholly within said casing and is mounted solely on said front plate, said means being of such dimensions relative to said opening that when said front plate is removed said means is removable through said opening while attached to said front plate, a contact feeler actuated part movably mounted on said casing independently of said front plate for actuating said reciprocator member, and spring means operatively carried by said front plate for urging said reciprocator member into contact with said contact feeler actuated part.

5. A dial micrometer gauge having, in combination, a casing having an opening and a removable front plate closing said opening, a movable indicator member operatively carried by said front plate, multiplying motion transmitting means comprising a reciprocator member, which means including said reciprocator member thereof is wholly within said casing and is mounted solely on said front plate, said means being of such dimensions relative to said opening that when said front plate is removed said means is removable through said opening while attached to said front plate, a bezel rotatably mounted on said front plate and removable therewith, and means readily accessible from the side of said casing opposite said front plate for removably securing the latter to said casing.

6. A dial micrometer gauge having, in combination, a supporting member formed to provide a casing, a removable front plate for the latter, an indicator member and a train of gearing for actuating the same carried by and removable with said front plate, said train being positioned within said casing and including a reciprocator rack, said supporting member being also formed to provide a removable guide member having a perforation opening into the interior of said casing, a contact feeler actuated part reciprocally mounted in said perforation in abutting laterally displaceable relation with said rack, and spring means for urging said rack into abutting contact with said contact feeler actuated part.

7. A dial micrometer gauge having, in combination, a casing having a perforated wall, an indicator member operatively carried by said casing, a motion transmitting train including a reciprocator member in said casing operatively carried thereby, a guide member removably carried by said casing coaxially with the perforation thereof, and a contact feeler actuated part separate from said reciprocator member reciprocally mounted upon said guide member for moving said reciprocator member, said contact feeler actuated part being removable with said guide member while said reciprocator member is in said casing.

8. A dial micrometer gauge having, in combination, a casing having a perforated wall, an indicator member operatively carried by said casing, a train of gearing including a reciprocator rack in said casing operatively carried thereby, a guide member removably carried by said casing coaxially with the perforation thereof, a contact feeler actuated part separate from said rack re-

ciprocally mounted upon said guide member for moving said rack, said contact feeler actuated part being removable with said guide member while said rack is in said casing, and means operative to prevent rotation of said contact feeler actuated part relative to said rack in the assembled gauge.

9. A dial micrometer gauge having, in combination, a casing, a movable indicator operatively carried by said casing, a reciprocator member in said casing for operating said indicator, said casing having an opening, a contact feeler actuated part extending through said opening into said casing operatively into abutting relation with said reciprocator member, a supporting member for said contact feeler actuated part removably attached to said casing whereby said contact feeler actuated part may be removed while said reciprocator part is in said casing, said contact feeler actuated part and one of said members operatively having cooperating means for preventing rotation of said contact feeler actuated part.

10. A dial micrometer gauge having, in combination, a casing including a removable front plate, an indicator member and a motion transmitting train for actuating the latter carried solely by and removable with said front plate, said train being positioned interiorly of said casing and including a reciprocator member, said casing having a member other than said front plate formed with a perforation, a perforated guide member removably carried by said member of said casing coaxially with the perforation thereof, and a contact feeler actuated part reciprocally mounted in the perforation of said guide member and being removable with the latter and operatively contacting with said reciprocator member of said train.

11. A dial micrometer gauge having, in combination, a casing including a removable front plate, an indicator member and a motion transmitting train for actuating the latter carried solely by and removable with said front plate, said train being positioned interiorly of said casing and including a reciprocator member, said casing having a member other than said front plate formed with a perforation, a perforated guide member removably carried by said member of said casing coaxially with the perforation thereof, a contact feeler actuated part reciprocally mounted in the perforation of said guide member and being removable with the latter and operatively contacting with said reciprocator member, and means for preventing rotation of said contact feeler actuated part relative to said guide member.

12. A dial micrometer gauge having, in combination, a casing, a movable indicator member operatively carried by said casing, means within said casing presenting a pair of movable cooperating stops, contact feeler actuated means for positioning one of said stops in accordance with the position of said contact feeler actuated means relative to said casing operative to move said stop in a direction which is away from the other stop upon decrease in the distance between said casing and the work surface with which the contact feeler contacts, motion transmitting means connecting said other stop to said indicator member, and spring means for yieldingly urging said other stop toward the first mentioned stop.

13. A dial micrometer gauge having, in combination, a casing, a movable indicator member operatively carried by said casing, means within said casing presenting a pair of movable cooperating

stops, contact feeler actuated means for positioning one of said stops in accordance with the position of said contact feeler actuated means relative to said casing operative to move said stop 5 in a direction which is away from the other stop upon decrease in the distance between said casing and the work surface with which the contact feeler contacts, motion transmitting means connecting said other stop to said indicator member, 10 spring means for yieldingly urging said other stop toward the first mentioned stop, and spring means acting yieldingly to urge the first mentioned stop toward the other stop under a greater force than that exerted by the first mentioned spring means 15 on said other stop.

14. A dial micrometer gauge having, in combination, a casing, a reciprocating contact feeler actuated part projecting from said casing, a movable indicator member operatively carried by 20 said casing, means within said casing comprising a pair of cooperating stop members, means for positioning one of said stop members in accordance with the position of said contact feeler actuated part relative to said casing operative to 25 move said stop member in a direction which is away from the other stop member upon inward movement of said part relative to said casing, a train of gearing connecting said other stop member to said indicator member, and spring 30 means operating on said gearing for yieldingly urging the last mentioned stop member toward the first mentioned stop member.

15. A dial micrometer gauge having, in combination, a rack, a pinion meshing with said rack, 35 an indicator member, gearing connected to said member for moving it, cooperating stop members associated with and moved by said pinion and gearing respectively, a contact feeler for moving said rack in one direction and spring means for 40 moving it in the opposite direction, said stop members being so arranged that when said rack is moved by said contact feeler it tends to move the stop associated with said pinion away from the other stop, and spring means associated with 45 said gearing for causing said gearing to urge its associated stop into contact with the stop associated with said pinion.

16. A dial micrometer gauge having, in combination, a support; a reciprocating rack, contact 50 feeler means for moving said rack in one direction, an indicator member, and gearing connecting said rack and indicator member, all carried by said support; said gearing comprising a rack pinion meshing with said rack and a gear coaxial with said pinion but mounted for rotation independently thereof, which gear is operatively connected to said indicator member for moving it; spring means acting on said gearing operative to cause said gear to rotate in the same direction 55 as said rack pinion when said rack is moved by said contact feeler means, and means forming a pair of cooperating stops one movable with said rack pinion and the other with said gear, said stops being so arranged that when said rack is

moved by said contact feeler means the stop movable with said rack pinion tends to move away from the other stop.

17. A dial micrometer gauge having, in combination, a casing member, a removable front plate for said casing member, a bezel and dial plate operatively rotatably mounted upon and removable with said front plate, an indicator hand cooperating with said dial plate also operatively mounted upon and removable with said 5 front plate, a contact feeler actuated part operatively mounted solely upon said casing member, a reciprocating rack member and a train of gearing operatively mounted solely upon and removable with said front plate for transmitting motion of said contact feeler actuated part to said indicator hand, and an operative connection between said rack member and said contact feeler actuated part permitting lateral displacement of one relative to the other, whereby said front 10 plate and the enumerated mechanism mounted thereon may be assembled as a unit independently of said casing member.

18. A dial micrometer gauge having, in combination, a casing member, a removable front 25 plate for said casing member, a bezel and dial plate operatively rotatably mounted upon and removable with said front plate, an indicator hand cooperating with said dial plate also operatively mounted upon and removable with said front 30 plate, a contact feeler actuated part, a removable bearing sleeve mounted solely upon said casing member, a contact feeler actuated part carried by and removable with said sleeve, a reciprocating 35 rack member and a train of gearing operatively mounted solely upon and removable with said front plate for transmitting motion of said contact feeler actuated part to said indicator hand, and an operative connection between said 40 rack member and said contact feeler actuated part permitting lateral displacement of one relative to the other, whereby said front plate and the enumerated mechanism mounted thereon may be assembled as a unit independently of said casing member.

19. A dial micrometer gauge having, in combination, a casing having a removable front plate, a bezel and a dial plate and cooperating indicator hand operatively mounted upon and removable with said front plate, a contact feeler actuated part mounted solely upon a member of said casing other than said front plate, a reciprocating member and cooperating motion transmitting means operatively mounted upon and removable with said front plate for transmitting motion 55 of said contact feeler actuated part to said indicator hand, said reciprocating member and contact feeler actuated part being so constructed as to abut with each other in the assembled device to permit removal of said front plate with the 60 enumerated parts mounted thereon, and spring means for urging said reciprocating member into contact with said contact feeler actuated part.

WARREN AMES.
